UNITED STATES PATENT OFFICE.

CHARLES A. DIETZ AND HARRY SCHUMAN, OF NEWARK, NEW JERSEY.

DESIGN FOR A FINGER RING.

Application filed February 10, 1923. Serial No. 5,133. Term of patent 7 years.

To all whom it may concern:

Be it known that we, CHARLES A. DIETZ and HARRY SCHUMAN, citizens of the United States, residing at Newark, in the county of Essex and State of New Jersey, have invented a new, original, and ornamental Design for a Finger Ring, of which the following is a specification, reference being had to the accompanying drawings, forming part thereof.

Figure 1 is a side elevation and Figure 2 is an edge view of a finger ring embodying our design.

We claim:—

The ornamental design for a finger ring as shown.

CHAS. A. DIETZ.
HARRY SCHUMAN.
